UNITED STATES PATENT OFFICE.

DANIEL L. LOTT, OF TIFFIN, OHIO, ASSIGNOR TO THE LOOMIS MACHINE COMPANY,
OF TIFFIN, OHIO.

LOAD CARRIER.

Application filed December 27, 1921. Serial No. 525,237.

To all whom it may concern:

Be it known that I, DANIEL L. LOTT, a citizen of the United States, residing at Tiffin, in the county of Seneca and State of Ohio, have invented a new and useful Load Carrier, of which the following is a specification.

This invention relates to a load carrying attachment designed primarily for use in connection with well drilling apparatus and other wheel supported structures designed to carry heavy loads which are applied thereto after the machine has been set in position, these heavy loads being ordinarily too great to be supported by the axle or axles of the vehicle.

Heretofore it has been the practice to use timbers which have been placed upon the supporting wheels of the machine before subjecting the mechanism to the excessive load but, as these timbers are heavy and unwieldy it is sometimes the case that the workmen will leave them behind and apply the load or weight to the mechanism without properly supporting it. As a result the axle will break and the work be delayed at a considerable expense.

It is an object of the present invention to overcome this objection by combining with a vehicle or machine of the character mentioned an adjustable means whereby the excess load can be applied to the supporting wheels and taken off of the axle without the use of some separate means which must be carried from place to place and set up in position for use.

A further object is to provide an attachment of this character which is simple and compact in construction and can be easily adjusted to secure the desired results.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the pre-

ferred form of the invention has been shown.

In said drawings—

Figure 1 is an elevation of a portion of a vehicle having the present improvements combined therewith.

Figure 2 is an enlarged section on line 2—2, Figure 1.

Figure 3 is a section on line 3—3, 60 Figure 2.

Referring to the figures by characters of reference 1 designates one of the axles of the vehicle provided with the usual supporting wheels 2, this axle supporting the bolster 3 on which is mounted the superstructure of the vehicle such, for example, as well drilling mechanism and the like. The superstructure has been indicated at 4. To the side sills 5 of the superstructure are secured plates 6 having inwardly extending flanges 7 at their lower edges which extend under the sills, these plates being fastened to the sills by bolts 8 or other suitable means provided for that purpose. Extending laterally from each of the plates is an ear 9 having a slot 10 extending thereinto from its outer edge. A guideway 11 is formed along the slot and within the bottom of the ear 9, this guideway constituting a seat for a nut 12 in which is mounted an adjusting screw 13. The lower end of the adjusting screw is swiveled within a foot 14, as shown at 15 while the upper end of the screw is provided with a head 16 for engagement by a wrench or other suitable tool.

As shown particularly in Figures 1 and 2 the slotted portion of the ear is reinforced by means of an upwardly extending portion 17 through which the slots 10 extend.

When the attachment herein described is properly placed on the vehicle the ears 9 will extend over but be spaced from the top-most portions of the wheels 2 and will be substantially in vertical alignment with the spindles of the axle 1. While the machine is being moved from place to place the feet 14 are located above and out of contact with the wheels. When the machine is properly positioned for taking on the excess weight, however, the screws 13 are adjusted so as to force the feet 14 downwardly onto the rims

of the wheels 2 and by exerting sufficient force the entire weight of the superstructure will be taken up by the screws 13 and transferred therethrough to the wheels 2. Thus the axle 1 is relieved of excessive strain.

By providing the slots 10 the screws 13 and the feet 14 can be adjusted laterally relative to the sills 5 so as to be properly positioned above the wheels 2.

10. What is claimed is:—

1. In a drilling machine of the class described the combination with an axle, supporting wheels therefor, and a superstructure normally supported by the axle, of laterally extending members connected to the superstructure and supported above the wheels, screws adjustable vertically within said members and laterally relative to the superstructure, and feet carried by the screws for engagement with the wheels to transfer the weight of the superstructure from the axle to the tops of the wheels, and to level the superstructure.

2. In a drilling machine of the class described the combination with an axle, supporting wheels therefor, and a superstructure normally supported by the axle, of laterally extending slotted members connected

to the superstructure above the wheels, screws extending upwardly through the members, means engaged by the screws and slidable on and held against rotation by the members for feeding the screws when rotated, and wheel engaging means carried by the screws for transferring the weight of the superstructure from the axle to the tops of the wheels and for leveling the superstructure.

3. A means for carrying the load of the superstructure of a wheel supported machine, said means comprising an ear, means for attaching the ear to a superstructure above the wheels of the machine, said ear being slotted, a screw extending downwardly through the slotted ear, means engaged thereby and slidable relative to the ear for feeding the screw when rotated, and wheel engaging means swiveled on the screw.

In testimony that I claim the foregoing as my own, I have hereto affixed my signature in the presence of two witnesses.

DANIEL L. LOTT.
